HEIGHT GAGE

Walter L. Lowry, Bethel, Conn., assignor to Montgomery & Company, Inc., Chatham, N.J., a corporation of New Jersey

Filed Mar. 12, 1964, Ser. No. 78,982

Term of patent 14 years

(Cl. D52—6)

FIGURE 1 is a front perspective view of a height gage showing my new design;

FIGURE 2 is an elevational view on a reduced scale of one side thereof, the other side being a mirror image thereof;

FIGURE 3 is a top plan view thereof; and

FIGURE 4 is a rear elevational view thereof.

I claim:

The ornamental design for a height gage, as shown and described.
